UNITED STATES PATENT OFFICE.

DANIEL P. FITZGERALD, OF NEWARK, NEW JERSEY.

COLLAR OR SLEEVE BUTTON.

SPECIFICATION forming part of Letters Patent No. 318,974, dated June 2, 1885.

Application filed February 14, 1885. (No model.)

To all whom it may concern:

Be it known that I, DANIEL P. FITZGERALD, a citizen of the United States, residing at Newark, in the county of Essex and State of New Jersey, have invented a new and Improved Collar and Sleeve Button; and I do hereby declare that the following is a full, clear, and exact description of the invention, which will enable others skilled in the art to which it appertains to make and use the same.

The object of my invention is to produce, with less labor and expense and without the use of solder, a collar or sleeve button stronger and better than those hitherto made. The obvious objection to such buttons, made of a number of different and separate pieces, has induced artisans in the trade of late years to make efforts to improve the buttons by reducing the number of pieces. As illustrative of the state of the art in this direction previous to this application, I refer to United States Patents Nos. 193,537, 202,412, 298,303, and 311,107.

My invention comprises a button having the head and shoe thereof both made in one piece, with the post from a metallic wire, and of varying thickness, according to the strain and consequent strength required.

In the accompanying drawings, Figure 1 represents in side view a wire-blank from which the button is made. Figs. 2 and 3 are vertical sections of the button in different stages of completion. Figs. 4 and 5 are vertical sections of the complete button with its post partly or wholly bored through or tubular.

By means of successive operations with suitable mechanical devices both ends of a piece of metal wire, B, Fig. 1, are simultaneously upset and then enlarged until they assume

the form of cross-section (shown in Fig. 2) suitable to constitute the head or front A and shoe or back C, respectively.

In the operation of enlarging, the metal is gradually drawn thinner from the post B toward the circumference, thereby giving increased thickness and strength at the points exposed to the greatest strain—for instance, as at a. At the stage of completion shown in Fig. 2 it is evident that all portions of the outer and inner surface of the button are accessible to the operation of polishing. The head A and shoe C are next operated upon, respectively, to assume the complete form shown in Fig. 3. When the button is made of gold, and it is desired to reduce its weight in order to save expense, the post B may for said purpose be bored out from the back, as shown in Fig. 4; and when a diamond or other precious stone is to be set in the center of the head the post B should be tubular—that is, the bore should go entirely through it to admit light, as usual, both below and above the diamond, in examining it, as shown in Fig. 5.

Having thus described my invention, I claim as new and desire to secure by Letters Patent—

1. A collar or sleeve button consisting of a single piece of metal wire having the head portion A and shoe portion C both integral therewith and both upset from the said wire, substantially as set forth.

2. A collar or sleeve button consisting of a single piece of metal wire having the head portion A and shoe portion C both integral therewith and both of varying thickness, substantially as and for the purpose described.

DANIEL P. FITZGERALD.
